UNITED STATES PATENT OFFICE.

JACOB KIILZ, OF PROVIDENCE, RHODE ISLAND, ASSIGNOR OF ONE-THIRD TO ROBERT J. MARTIN, ONE-THIRD TO ROBERT J. PROHASKA, AND ONE-THIRD TO DENNIS CONNOR, ALL OF NEW YORK, N. Y.

SPARK-GAP.

1,183,011.

Specification of Letters Patent.

Patented May 16, 1916.

Application filed July 26, 1915. Serial No. 42,047.

To all whom it may concern:

Be it known that I, JACOB KIILZ, a citizen of the United States, residing at Providence, in the county of Providence and State of Rhode Island, have invented certain new and useful Improvements in Spark-Gaps, of which the following is a specification.

My invention relates to spark gaps or similar attachments to spark plugs and is 10 purposed for those general objects characteristic to this type of structure.

In addition to the above the essential objects of my invention are to afford a closer set of the adjacent gap elements than has 15 heretofore been possible; to accommodate these elements more closely to the relatively small actual voltage of the passing current, and to the variation in voltage due to whether the connection happens to be from 20 the dry cell battery or from the magneto; to prevent jumping of the spark across the gap by centering the current at that point; to insure a maximum insulation thereby 25 preventing short circuiting; to provide an ample air circulation around the contacts to prevent excessive heat, fusion, or oxidation 30 of the parts; to prevent fracture of the glass wall by vibration; to improve the clamp connection; and to attain these objects in an inexpensive structure.

To the above ends my invention consists in such parts and combinations of parts as fall within the scope of the appended claims.

In the accompanying drawings which 35 form a part of this specification, Figure 1 is a plan view of my novel gap, Fig. 2, a longitudinal section of the same on line 2-2 of Fig. 1, Fig. 3, a transverse section on line 3-3 of Fig. 1, and Figs. 4 and 5, 40 opposite end elevations of the same.

Like reference characters indicate like parts throughout the views.

My device comprises two caps 1 and 2 of insulating material, the former comprises 45 an end wall 3, and an inwardly directed peripheral flange 4. Integral with this cap and concentric thereto is a body 5 of fiber or other insulating material preferably moldable. This body or core is substantially cylindrical except that it has plain surfaces 6 at diametrically opposite points separated by curved surfaces 7 as shown in Fig. 3. The core is provided with a central transversely disposed opening 9, ex-

tending therethrough to the flat or plain 5 surfaces 6. The cap and body has a central axial opening 10 provided with threads 11. This opening extends from the outer face of the cap body to the transverse opening 9.

In alinement with the opening 10 the 60 body has an opening 13 provided with threads 14 and extending from the opening 9 to the end face of the body. Abutting against this face is the wall 16 of the cap 2 provided with a peripheral flange 17. 65 This cap is also of insulating material. A central threaded opening 19 in the cap head 16 is in alinement with the opening 13.

A fixed conductor 21 has threads 22 engaging the threads 11 of the body, while a 70 rotary conductor 24 has external threads 25 engaging the threads 14 of the body, and in the threaded opening 19 of the cap 2. The rod 24 has a milled or knurled head 27 upon its outer end, and upon its projecting 75 shank is threaded a lock nut 28 and a nut 29 adapted to engage therebetween a current conducting wire 30. Fixed to or integral with a head 31 on the outer end of the screw member 21, is a clip or clamp 32 comprising a flat plate 33 provided with a deep curved marginal cavity 34 to which extends a slot 35 forming flat curved resilient fur- 80 cations of fingers 36 adapted to clasp the rod of the spark plug to which my device 85 is applied.

The adjacent inner ends of the screw members or threaded rods 21 and 24 are flat, and carry in chamber 9 concentrically located pins or projections 39 and 40, of 90 reduced diameters in alinement with each other, and provided with flat end faces.

Rotatably mounted on the body 6 is a cylindrical transparent or glass shell or tube 41, of slightly less length than said 95 body, and loosely overlapped by the flanges 4 and 17 of the caps. The flat character of the opposite sides of the body, or its semi-cylindrical character, combined with the cylindrical form of the shell or tube 6 forms 100 opposite longitudinal chambers 42 and 43 connected by the opening 9.

In the wall 3 are air perforations or pas- 105 sages 45 and 46 extending to chambers 42 and 43 respectively; and in the wall 16 are similar passages 48 and 49 opening into the respective chambers.

The parts assembled as described consti-

tute a structure wherein the gap members are set by manually turning the head 27 whereby the element 40 on the movable member 24 is caused to approach or recede from the element 31 of the relatively fixed or stationary member 21.

It will be understood that the member 21 may be fixed in the body 6 in any desired manner. The small diameter of the coöperating projections and the flat character of their faces admit a close approach or set, and their reduced diameter relatively to the carrying members 21 and 24 centers the current and prevents spark jumping. Excessive heat of and adjacent to projections or contacts 39 and 40 is prevented by the ample air circulation passing through the air channels, the longitudinal chambers, and the transverse chamber 9.

20 The rotary and slidable character of the transparent shell 41 prevents the fracture thereof by the vibration of the object carrying the gap structure. The clip or clamping member 32 makes it possible to engage the structure to a plug rod without auxiliary nuts, if desired.

What I claim is:—

1. In a spark gap, the combination of a cylindrical insulating body provided with 30 oppositely disposed plane side faces and with a transverse chamber extending through the body to the plane faces, a cylindrical glass shell surrounding the body and forming with the plane faces longitudinal

chambers, caps upon the ends of the body 35 provided with perforations leading to the longitudinal chambers, conductors in the body extending into the transverse chamber, and spark projections upon the conductors.

2. In a spark gap, the combination of an insulating body provided with oppositely disposed plane peripheral faces and with a transverse chamber extending through the body to the plane faces, a shell surrounding 45 the body and forming with the plane faces longitudinal chambers, caps upon the ends of the body provided with perforations leading to the longitudinal chambers, conductors in the body extending into the transverse chamber, and spark projections upon the conductors.

3. In a spark gap, the combination of an insulating body provided with a transversely disposed chamber extending through the 55 body, a shell surrounding the body and forming in conjunction therewith longitudinal chambers communicating with the first chamber, and caps upon the body provided with perforations communicating with the 60 longitudinal chambers.

In testimony whereof I have affixed my signature in presence of two witnesses.

JACOB KIILZ.
